UNITED STATES PATENT OFFICE.

THOMAS J. STRAIT, OF WILLIAMSPORT, PENNSYLVANIA.

REBOUNDING-PLUNGER PRESS.

SPECIFICATION forming part of Letters Patent No. 449,601, dated March 31, 1891.

Application filed November 21, 1890. Serial No. 372,209. (No model.)

To all whom it may concern:

Be it known that I, THOMAS J. STRAIT, a citizen of the United States, residing at Williamsport, in the county of Lycoming and State of Pennsylvania, have invented certain new and useful Improvements in Rebounding-Plunger Presses; and I do hereby declare the following to be a full, clear, and exact description of the invention, such as will enable others skilled in the art to which it appertains to make and use the same.

My invention has relation to that class of presses known as "rebounding plungers."

The object is to improve upon the mechanism for operating the plunger; and to that end the invention consists of constructions and combinations, as will hereinafter be set forth in the specification, and pointed out in the claims, reference being had to the accompanying drawings, in which—

Figure 1 represents a top plan showing one of the positions of the operating mechanism; Fig. 2, a similar view showing the same parts in a different position and the radii or arms 25 of the toggle-lever on a right line in full lines and the next position in dotted lines; Fig. 3, a side elevation of part of the device; and Fig. 4, a section on line 4-4, Figs. 1 and 2.

The press and frame-work A of the machine 30 are substantially the same as all devices of this class, so only so much of the frame A is shown as will give the necessary supports to the improved device. The frame A is provided with a vertical pin or shaft A', set up 35 and supported in the usual manner on the same longitudinal line that the plunger is worked upon. Upon this shaft is a wheel A², which may be loose upon the shaft if the shaft be fixed, or fixed or loose upon the shaft 40 if the latter be loose. This wheel is provided with a lever or sweep A³, by which it is partially rotated upon its axis in the manner common in this class of devices. The rim a of the wheel on the side opposite to that to 45 which the sweep is secured is cut away at a' to form a recess or track a², which terminates at each end in a recess or stop a³, having lips a⁴. The track is on a curve or arc of a circle of less diameter than the wheel, and has a 50 sub-track formed by the rabbet a⁵.

B represents the toggle-levers arranged in pairs, the arms b of one pair being pivoted

at one end to the plunger, and the arms b' of the other pair being pivoted to the shaft A', one above and the other below the wheel A², 55 and hinged or connected to the arms b by a pintle b², placed vertically at a point about midway between the track a² and the arc described by the lips a⁴ when the wheel is turned. This brings the pintle b², when the wheel is ready to move from either side, directly in the path of the stops a³, so that when the wheel is moved it forces the pintle to advance with the stop that it happens to be engaged with until the arms of the toggle 60 have passed the right line, when it is released by reason of the back-pressure of the hay acting to deflect the arms of the toggle in the opposite direction. This movement of the arms of the toggle moves the pintle into the 70 recess or stop a³ opposite to that which it had just left, so as to be ready to move the toggle in a reverse direction.

To guide the pintle to its proper place, a block B' is interposed between the arms b and b' and pivoted on the pintle b², and fitted to the tracks a² and a⁵ by rabbeting the face b². The corners b⁴ may also be beveled to fit into the recess or stop a³ and overlapped by the lips a⁴ to prevent the block from jumping out or bending the pintle when sent into the stop a³ by a rebound. The block also 75 protects the pintle to a great extent, and in fact prevents it from bending when the blows due to the rebound are very hard. In practice buffers are placed in the recesses or stops a³ to moderate the jar as much as possible.

The device is operated as follows: Hay being placed in the press, the sweep is moved 90 around the end of the machine until the pintle of the toggle has been moved over the right line, so as to press the hay and then give the back-pressure a chance to act to bend the toggle-lever. As soon as the pintle 95 passes said right line the back-pressure throws the block around the recess or track a² until it reaches the opposite stop from which it started. The movement of the sweep is now reversed to produce the same 100 result in an opposite direction of draft.

What I claim as new is—

1. In a press of the kind described, the combination of a wheel having an arc-shaped

recess in its periphery, and a toggle-lever the hinge-pintle of which is held by the arms of the toggle in said recess and is moved by contacting with the stops at the ends of said recess when the wheel is moved.

2. In a press of the kind described, the combination of a wheel having an arc-shaped recess and track in its periphery, and a toggle-lever having on its hinge-pintle a block which rests upon said track and is moved by the ends of the recess contacting therewith when the wheel is moved.

3. In a press of the kind described, the combination of a wheel having the recess with the overlapping lips at the end, and a toggle-lever having a pintle in the same arc of the circle that the recessed part of the wheel moves in.

In testimony whereof I affix my signature in presence of two witnesses.

THOS. J. STRAIT.
